UNITED STATES PATENT OFFICE.

IRVIN F. LEHMAN, OF PITTSBURGH, PENNSYLVANIA, ASSIGNOR TO BLOW-KNOX COMPANY, OF BLOWNOX, PENNSYLVANIA, A CORPORATION OF NEW JERSEY.

ANNEALING-BOX BOTTOM.

Application filed March 14, 1922. Serial No. 543,572.

To all whom it may concern:

Be it known that I, IRVIN F. LEHMAN, a citizen of the United States, residing at Pittsburgh, in the county of Allegheny and State of Pennsylvania, have invented a new and useful Improvement in Annealing-Box Bottoms, of which the following is a full, clear, and exact description.

The present invention relates to annealing box bottoms. The box bottom is corrugated and thereby secures certain important and novel advantages as hereinafter described.

In the drawings,—

Figure 1 is a plan view;

Figure 2 is a section along the line II—II of Figure 1 and also indicates in dotted lines the box;

Figure 3 is a section along the line III—III of Figure 1; and

Figure 4 is a section along the line IV—IV of Figure 1.

Referring to the illustrated embodiment of the invention, the annealing box bottom consists of a single integral sheet 1 of steel of substantially uniform thickness throughout and having the corrugations 2 and 3 formed therein. The sheet may be made of sheet steel in which the corrugations are pressed, or may be made of cast metal, such as iron or steel cast into sheet form with the corrugations formed therein by casting.

The deeper corrugations 2 form legs which keep the body of the box bottom spaced above the floor of the annealing furnace so that the heating gases may pass freely under the box. The legs also permit the ready insertion beneath the box of the prongs of the usual gooseneck annealing box lifter.

The metal is of substantially the same thickness throughout the box bottom, and therefore of substantially the same heat conductivity throughout, so that there is a substantially even distribution of heat over the entire bottom, and it is thus possible to avoid cold spots such as are formed when legs or thickened places are formed on the bottom.

Shallower corrugations 3 extend at right angles to the corrugations 2. The system of cross corrugations stiffens the bottom.

The metal of the bottom is of a thickness substantially the same as or comparable with

that of the annealing box 4 which is indicated in dot and dash lines in Figure 2. A substantially uniform heating of the pack of sheets, both top and bottom, is thus permitted. The usual practice has been to make annealing box bottoms of cast iron, which have been much thicker than the box portion proper, and have therefore required so much heat to anneal the bottom of the pack that the top of the pack has often been burned before the bottom has been sufficiently annealed. Attempts to remedy this defect, have been made by constructing the bottom of thinner metal with legs riveted or welded thereto. Such legs are apt to burn or scale off, are expensive to apply, and make spots where the mass of the metal is increased and is therefore colder than the intermediate portions of the bottom. As can readily be seen, my annealing box bottom permits ready conductivity of heat to the bottom of the pack, but at the same time it is strong and stiff, has no legs to burn or scale off, and can be made at a moderate cost.

While I have specifically illustrated and described a preferred embodiment of my invention, it is to be understood that the invention is not limited to its illustrated embodiment but may be embodied in other constructions of annealing box bottoms within the scope of the following claims.

I claim:

1. An annealing box bottom having corrugations forming box supporting legs for maintaining the body of the box bottom spaced above the floor of the annealing furnace, there being openings communicating with the space between the corrugations and the combustion space of the furnace when the box is in the furnace for permitting the access of heating gases therebeneath, substantially as described.

2. An annealing box bottom having a substantially uniform thickness of material throughout and having corrugations forming box supporting legs for maintaining the body of the box bottom spaced above the floor of the annealing furnace there being openings communicating with the space between the corrugations and the combustion space of the furnace when the box is in the

furnace for permitting the access of heating gases therebeneath, substantially as described.

3. An annealing box bottom having corrugations forming box supporting legs for maintaining the body of the box bottom spaced above the floor of the annealing furnace and permitting the access of heating

gases therebeneath, and having additional shallower corrugations for giving additional strength to said box bottom, substantially as described. 10

In testimony whereof I have hereunto set my hand.

IRVIN F. LEHMAN.
